US00D570686S

(12) **United States Design Patent** (10) **Patent No.:** **US D570,686 S**
(45) **Date of Patent:** **** Jun. 10, 2008**

(54) **DISPOSABLE CUP LID**

(75) Inventors: **Robert W. Hollis**, Homer Glen, IL (US); **Weston S. Koennecke**, Oak Park, IL (US); **John R. Geer, III**, Downers Grove, IL (US)

(73) Assignee: **Pactiv Corporation**, Lake Forest, IL (US)

(**) Term: **14 Years**

(21) Appl. No.: **29/250,410**

(22) Filed: **Nov. 13, 2006**

(51) **LOC (8) Cl.** **09-07**

(52) **U.S. Cl.** **D9/447; D9/449; D9/454**

(58) **Field of Classification Search** **D9/600, D9/454, 453, 452, 449, 447, 445, 438, 435; D7/392.1; 220/711-713, 268, 266, 254, 220/254.3-254.9, 254.1; 229/906.1**

See application file for complete search history.

(74) *Attorney, Agent, or Firm*—Bell, Boyd & Lloyd LLP

(57) **CLAIM**

The ornamental design for a disposable cup lid as shown and described.

DESCRIPTION

FIG. 1 is a rear perspective view of a disposable cup lid of our new design, that portion of the cup lid shown in broken lines is not part of the claimed design and is provided for environmental purposes only.

FIG. 2 is a top plan view of the disposable cup lid of our new design illustrated in FIG. 1, that portion of the cup lid shown in broken lines is not part of the claimed design and is provided for environmental purposes only.

FIG. 3 is a bottom plan view of the disposable cup lid of our new design illustrated in FIG. 1, that portion of the cup lid

shown in broken lines is not part of the claimed design and is provided for environmental purposes only.

FIG. 4 is a rear side view of the disposable cup lid of our new design illustrated in FIG. 1, that portion of the cup lid shown in broken lines is not part of the claimed design and is provided for environmental purposes only.

FIG. 5 is a front side view of the disposable cup lid of our new design illustrated in FIG. 1, that portion of the cup lid shown in broken lines is not part of the claimed design and is provided for environmental purposes only.

FIG. 6 is a left side view of the disposable cup lid of our new design illustrated in FIG. 1, the right side being a mirror image thereof, that portion of the cup lid shown in broken lines is not part of the claimed design and is provided for environmental purposes only.

FIG. 7 is a rear perspective view of an alternative embodiment of the disposable cup lid of our new design, that portion of the cup lid shown in broken lines is not part of the claimed design and is provided for environmental purposes only.

FIG. 8 is a top plan view of the disposable cup lid of our new design illustrated in FIG. 7, that portion of the cup lid shown in broken lines is not part of the claimed design and is provided for environmental purposes only.

FIG. 9 is a bottom plan view of the disposable cup lid of our new design illustrated in FIG. 7, that portion of the cup lid shown in broken lines is not part of the claimed design and is provided for environmental purposes only.

FIG. 10 is a rear side view of the disposable cup lid of our new design illustrated in FIG. 7, that portion of the cup lid shown in broken lines is not part of the claimed design and is provided for environmental purposes only.

FIG. 11 is a front side view of the disposable cup lid of our new design illustrated in FIG. 7, that portion of the cup lid shown in broken lines is not part of the claimed design and is provided for environmental purposes only; and,

FIG. 12 is a left side view of the disposable cup lid of our new design illustrated in FIG. 7, the right side being a mirror image thereof, that portion of the cup lid shown in broken lines is not part of the claimed design and is provided for environmental purposes only.
